UNITED STATES PATENT OFFICE.

GEORGE H. NORTH, OF LA CROSSE, KANSAS.

SHIM-CUTTING PRESS.

Application filed April 14, 1923. Serial No. 632,074.

To all whom it may concern:

Be it known that I, GEORGE H. NORTH, a citizen of the United States, residing at La Crosse, in the county of Rush and State 5 of Kansas, have invented new and useful Improvements in a Shim-Cutting Press, of which the following is a specification.

This invention relates to a shim cutting press and has for its primary object to produce a simple and easily operated construction.

A further object is to produce a shim cutting press in which both the male and female dies are removably secured thereon 15 whereby dies of varying sizes and shapes may be employed.

A further object is to produce a shim cutting press in which the dies will have a shearing action in the cutting of the shim; 20 wherein the cut shim is automatically ejected; wherein the plunger carrying the male die is contacted by one of two cam surfaces on an operating lever whereby different size shims may be cut, and also whereby 25 a plurality of such shims may be cut in a single operation.

With these and other objects in view, this invention will be better understood from the following detailed description taken in 30 connection with the accompanying drawings wherein:

Figure 1 is a front elevation of a shim cutting press in accordance with this invention.

Figure 2 is a side elevation thereof.

Figure 3 is a sectional view on the line 3—3 of Figure 1.

Figure 4 is a sectional view on the line 4—4 of Figure 2.

Figure 5 is a perspective view of the male die member.

Figure 6 is a similar view of the female die member.

Figure 7 is a similar view of the bed plate upon which the female die member rests.

Figure 8 is a similar view of the ejector.

Figure 9 is a sectional view on the line 9—9 of Figure 7.

Again referring to the drawings, the numeral 1 designates the flat base of the improvement. From the rear of the base there arises a standard 2 having its upper end provided with a transverse rounded bore 55 that receives therethrough the shaft 3 of the operating handle 4. Below the handle

the standard is formed with an integral extension that terminates in a vertically disposed sleeve 5, and through this sleeve the cross sectionally rounded plunger member 6 of the device moves. The plunger has its upper end provided with a transverse slot 7 and below the slot with an annular enlargement 8. Surrounding the plunger in contacting engagement with the upper end of the sleeve and the lower wall of the enlargement 8 there is a helical spring 9 of a sufficient strength to normally hold the plunger elevated.

The handle 4 has its inner end flat and has secured preferably by removable means 10 thereon an enlargement 11. The enlargement is in the nature of a block whose outer end is rounded to provide a cam surface 12 that terminates in an inwardly directed shoulder 13, and from this shoulder the block is shaped to provide a second cam surface 14.

The lower end of the plunger 6 is hollow and receives therein the stem 15 of the male die 6. Suitable binding means 17 carried by the plunger engages the stem 15 to hold the die 16 properly positioned on the plunger.

By reference to the drawings it will be noted that the cutting surface of the die 16 is arranged at an inclination with respect to the base 1 so that a shearing action against the metal producing the shim will be obtained and the said metal cut in an easier manner than were the active face of the die straight.

Resting on the base 1 directly below the die 16 there is the bed plate 18 for the female die plate 19. The plate 19 has openings therethrough for screws 20, the said screws passing through similar openings in the base 1. The die plate has other openings adjacent to the diagonal corners thereof that receive therethrough pins 21 carried by 100 the bed plate.

The male die is, of course, provided with the usual rounded central enlargement, the female die having its walls correspondingly shaped. The bed plate is centrally provided with a rounded projection 22 that provides a guide for an ejector member or plate 23. The ejector 23 is, of course, shaped to correspond with the walls of the female as well as the male die member and is provided with 105 spaced studs 24 that pass through the bed plate 18 and have their heads 25 received

in depressions 26 in the base 1. Surrounding the studs and exerting a pressure between the ejector plate and the bed plate there are helical springs 27. The plate 23 is depressed when the male die enters the female die so that the cut shim will rest directly on the said plate. When the male die is raised out of the female die, the springs 27 will force the plate 23 to normal position, as illustrated in Figure 9, so that the cut shims will be ejected by the said plate.

The construction of the improvement will, it is thought, be apparent from the foregoing description and the operation will likewise be apparent to those skilled in the art to which such inventions relate. Varying sizes of both male and female dies may be employed, the female die plate, however, being provided with openings for the sustaining screws and for the pins carried by the bed plate. The outer cam member will act in the slotted head of the plunger to force the male die partly into the female die when comparatively thin shims are to be made. The second or inner cam member acts upon the plunger to further force the male die into the female die when a plu-

rality of shims or when a single shim of a determined thickness is to be cut. The double cam arrangement on the handle permits of an easier operation of the plunger and male die than would be afforded were only a single cam employed, and while I have herein set forth a satisfactory embodiment of the improvement as it now appears to me, it is to be understood that I may make such changes therefrom as fall within the scope of what I claim.

Having described the invention, I claim:—

In a shim cutting press, a base, a standard arising therefrom, a handle member swingably supported on the standard, an enlargement removably secured on the inner end of the handle having two spaced cam surfaces, a spring influenced plunger supported for vertical movement on the standard and having a slotted upper end in which the cam enlargement on the handle is received, a male die removably secured to the plunger, a bed plate resting on the base, a female die plate guided on the bed plate removably secured thereto and to the base, and a spring influenced ejector in the female die member.

In testimony whereof I affix my signature,
GEORGE H. NORTH.
